COSMETIC BRUSH

Eric Victor Aylott, Welwyn Garden City, England, assignor to Eylure Limited, Garden City, England, a British company

Filed May 17, 1965, Ser. No. 85,314

Claims priority, application Great Britain Feb. 3, 1965

Term of patent 14 years

(Cl. D9—2)

Fig. 1

Fig. 2.

Fig. 3.

Fig. 4.

FIG. 1 is a side view of a cosmetic brush showing my new design and illustrating the brush and cover members in open position;

FIG. 2 is a perspective view illustrating the brush and cover members in the open position;

FIG. 3 is a bottom plan view with the brush and cover members in closed position; and

FIG. 4 is a top plan view showing brush and cover members in closed position.

Both sides of the brush have identical appearances.

I claim:

The ornamental design for a cosmetic brush, as shown and described.
